H. W. MARTIN

ADJUSTABLE TRAY FOR CHILD'S CHAIR

Filed Aug. 10, 1927

UNITED STATES PATENT OFFICE.

HAROLD W. MARTIN, OF SAN BERNARDINO, CALIFORNIA.

ADJUSTABLE TRAY FOR CHILD'S CHAIR.

Application filed August 10, 1927. Serial No. 211,936.

My invention is an adjustable tray for a child's chair.

An object of my invention is the construction of a tray which may be adapted to a child's chair such as a high chair and adjusted in various positions to hold the child securely in the chair and also be loosened and hang downwardly at the side of the chair.

10 Another object of my invention is the construction of a child's chair with metal guideways on the arm rests, these guideways supporting and guiding the sliding motion of a tray in a horizontal direction, together with 15 a latching device for latching the tray in any desired position in the guideways. One of the guideways extends around the end of the arm and on the outside, and is provided with means for allowing the tray to hang 20 downwardly.

In constructing my child's chair with the adjustable tray, I provide a pair of metal guideways having a longitudinal depression in which the edges of the tray may slide. 25 The guideways facing each other on the arms of the chair are provided with a plurality of perforations in which the latches or sliding bolts carried by the tray may engage and hold the tray adjusted in various 30 positions. One of the guideways is provided with a longitudinal slot in which a screw or bolt or the like having a head may slide, the head being on the inside of the slot and traveling in a groove cut in the 35 wood-work of the arm rest.

The guideway on one of the arms is bent around the end of the arm and extends towards the back of the chair on the outside, and has a continuation of the slot in which 40 the bolt operates, this slot being turned downwardly to the under side of the arm rest so that the tray may hang downwardly from such arm rest. There is also a key hole type of slot at the end so that the bolt, 45 and hence the tray, may be entirely removed if desired.

My invention in its various aspects will be more readily understood from the following description and drawings, in which: 50 Figure 1 is a perspective view of a chair with my tray installed thereon.

Figure 2 is an underneath view of the tray and of the arm rests taken in the direction of the arrow 2 of Fig. 1.

Figure 3 is a vertical transverse section 55 taken substantially on the line 3—3 of Figs. 1 or 2 in the direction of the arrows.

Figure 4 is an inside elevation taken in the direction of the arrow 4 of Fig. 1 showing one of the guideways. 60

Figure 5 is an outside elevation taken in the direction of arrow 5 of Fig. 1 showing the guide slot on the outside of the arm rest. 65

Figure 6 is a horizontal longitudinal section on the line 6—6 of Fig. 5 in the direction of the arrows.

Figure 7 is a vertical transverse section on the line 7—7 of Fig. 5 in the direction of the arrows. 70

Figure 8 is a transverse section of the left arm rest similar to Fig. 3 with the tray hanging downwardly.

The guideways on the inside of the arm rests 11 comprise a metal guideway 12 which 75 has a vertical web 13 and horizontal flanges 14. The guideway is fitted in a recessed section 15 of the arm rest and is provided with a plurality of perforations 16, for a purpose set forth hereunder, and with a 80 longitudinal slot 17. Inside this slot the wood is cut away, forming a longitudinal groove 18.

The guideway on the right arm rest is 85 illustrated as terminating at the outer end or nose 19 of such arm rest, whereas on the left arm rest the metal strip forming the guideway is bent around the end, as illustrated at 20, and continued on the outside of the arm rest, as indicated at 21. The 90 shape, however, is different from the guideways on the inside. In this case there is a metal strip or band 22 which encircles the end and passes part way along the outside of the arm rest. This has a longitudinal slot 95 23 which joins into the slot 17 on the inside guideway, the slot following the curvature of the nose of the arm rest and also along the outside. The metal is then bent under the arm rest as indicated at 24 and 100 the slot is also turned downwardly, as indicated at 25.

There is a connecting slot 26 connecting with the vertical slot 25 and extending underneath the arm rest followed by a slot 27 105 a short length, running lengthwise of the arm rest and terminating in a round key hole opening 28.

The wood of the left arm rest has a cut-out groove 29 following around the end or nose of the arm rest and on the outside underneath the metal strip 22, these metal structures forming the guideways. The strip may be secured to the arm rest in any suitable manner, and it is preferable to make the metal structure on the left arm rest integral.

10 The tray 30 is indicated as having an inner concave curved edge 31 and an outer convex curved edge 32, with a pair of depending flanges 33 on the sides, as well as with depending lugs 34 in about the center 15 of the tray.

Latch bolts 35 are slidably mounted in the flanges 33 and the lugs 34, each of these having a finger grip 36 on the inner end. Also each of the latch bolts is provided with an 20 adjustable collar 37 and with a coiled compression spring 38 tensioned between the lug 36 and the collar 37, thus the spring normally tends to thrust the latch bolts outwardly. One of the flanges is provided with a 25 suspending bolt or screw 39 having a head 40, the head fitting in the grooves 18 and 29 in the left arm rest.

The manner of using and functioning of my child's chair with the tray is substantially as follows:

After the child is seated in the chair, and presuming the tray is hanging as shown in Fig. 8 suspended by the bolt in the short slot 26 or 27, the tray may then be shifted, the 35 bolt following in the angular slots and making the various turns, also following around the slot 23 which merges into the slot 17. In this motion the head of the bolt follows the groove 29 and then the groove 28 in the 40 wood of the arm rest. The flanges 33 of the tray are then guided in the metal guideways of both of the arm rests, and when the concave edge 31 of the tray is pressed close to the child, the finger grips 34 are operated 45 so that the ends of the bolt latches 35 fit in opposite apertures 16 of the guideways; the tray may thus be adjusted so close to the child that it is impossible for the child to slip downwardly between the tray and the 50 seat of the chair or to climb upwardly at the back of the chair.

When it is desired to release the child, the finger grips 36 are drawn together, compressing the spring 38 and thus releasing 55 the bolts from the apertures; the tray may then be swung outwardly, and by being turned around, the bolt 39 following in the slots and grooves above mentioned, in the reverse manner, the tray is then positioned 60 so that it may hang vertically as shown in Fig. 8. If it is desired to remove the tray entirely from the chair, the bolt head may be passed through the key hole circular end of the slot 38.

65 From the above description it will be seen

that the type of hardware used may be adapted for different forms of trays or other arrangements for securing children in chairs, or the like. It is also apparent that the mechanism may be reversed so that the tray 70 may hang from the right arm rest instead of the left.

Various changes may be made in the principles of my invention without departing from the spirit thereof, as set forth in the 75 description, drawings and claims.

I claim:

1. In the art described, a chair having arm rests with guideways secured thereto, a tray 80 slidable in said guideways, one of said guideways having a longitudinal slot, a latching means connected with the tray and interacting with the guideways to adjustably latch the tray, and a holding device secured to the tray and extending through the said slot, the said holding device permitting the disengagement of the tray from the guideways and being adapted to retain the tray connected to one of the arm rests.

2. In the art described, the combination 90 of a chair having arm rests with guideways therein, a strip or track connected to one of the guideways, said latter guideway and strip or track having a slot, a tray fitted in the guideways having a latching means 95 adjustably securing the tray, and a retaining device secured to the tray and engaging in said slot, permitting the disengagement from the tray with the guideways but retaining the tray secured to one of the arm 100 rests.

3. In the art described, as claimed in claim 2, the latching means comprising a series of perforations in the guideways, a plurality of latching bolts slidably mounted on the tray, 105 and means to engage or disengage the latching bolts in the perforations.

4. In the art described, the combination 110 of a chair having arm rests with a plurality of guideways secured thereto, one of the guideways having a strip or track connected thereto, the said latter guideway and the strip or track having a connecting slot, the track being on the outside of the arm rest and turning the outside end of such rest, 115 a tray having opposite edges fitted in the guideways, a bolt having a head on one side of the tray and fitting in the said slot, the said bolt permitting disengagement of the tray from the guideways and shifting the tray from between the arm rests to the outside of one of the arm rests.

5. In the art described, as claimed in claim 4, the slot having means to turn the tray from a horizontal to a vertical position 125 depending on the outside of the arm rest.

6. In the art described, as claimed in claim 4, the slot in the track on the outside of the arm rest being down-turned and extending underneath the arm rest, said slot forming a 130

- guide in the movement of the bolt, whereby the bolt may hold the tray suspended beneath the arm rest.
7. In the art described, as claimed in claim 4, the slot in the track on the outside of the arm rest being down-turned and extending underneath the arm rest, said slot forming a guide in the movement of the bolt, whereby the bolt may hold the tray suspended beneath the arm rest, the slot underneath the arm rest terminating in a circular or key hole opening and allowing the bolt head to pass therethrough for disengagement of the tray from the arm rest.
8. In the art described, a chair having a pair of arm rests, each having a guideway with perforations therein and one having a longitudinal slot, a strip or track connected to the guideway having a slot, said track being on the outside of the arm rest, the slot continuing around the end of the arm rest and longitudinally of the track, a tray having a plurality of latching bolts slidably mounted thereon, means to engage and disengage the bolts from the said perforations, a bolt having a head connected to one side of the tray and engaging in the said slot, the bolt allowing disengagement of the tray from the guideways and retaining the tray attached to the track on the outside of the arm rest.
9. In the art described, as claimed in claim 8, the guideways having a web adapted to fit in a recess in the arm rests and having upper and lower horizontal flanges, the lower flanges supporting the tray.
10. In the art described, as claimed in claim 8, the guideways being formed of metal and fitted in recesses in the arm rests, and the strip or track being substantially flush with the outside surface of one of the arm rests, said strip or track having a terminating end fitted underneath the arm rest, the slot extending underneath and allowing suspending of the tray vertically underneath the arm rest.
11. In a chair having arms, a groove extending longitudinally of the arms in the inner face thereof and open at its forward end, of a tray detachably slidably mounted in said groove and lying between said arms, and means carried by the tray and operable in the groove to lock it in an adjusted position within said groove.
- In testimony whereof I have signed my name to this specification.

HAROLD W. MARTIN.
